(57) **CLAIM**

The ornamental design for a multifunctional vegetable chopper and slicer set, as shown and described.

DESCRIPTION

FIG. 1 is a top and front perspective view of components of a multifunctional vegetable chopper and slicer set showing my new design;

FIG. 2 is a top perspective view of a first component;

FIG. 3 is a bottom perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view thereof shown in a state of use;

FIG. 11 is a top perspective view of a second component;

FIG. 12 is a bottom perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof;

FIG. 19 is a perspective view thereof shown in a first state of use;

FIG. 20 is a perspective view thereof shown in a second state of use;

FIG. 21 is a top perspective view of a third component;

FIG. 22 is a bottom perspective view thereof;

FIG. 23 is a front elevational view thereof;

FIG. 24 is a rear elevational view thereof;

FIG. 25 is a left side elevational view thereof;

FIG. 26 is a right side elevational view thereof;

FIG. 27 is a top plan view thereof;

FIG. 28 is a bottom plan view thereof;

FIG. 29 is a perspective view thereof shown in a state of use; and,

FIG. 30 is an exploded view thereof, shown in an environment of use.

(Continued)

The broken lines showing of the container and blades in FIGS. 19, 20, and 30 illustrate environmental subject matter and form no part of the claimed design.

All other broken lines in the drawings depict portions of the multifunctional vegetable chopper and slicer set that form no part of the claimed design.
